CLAIM

The ornamental design for a sterilization container, as shown and described.

DESCRIPTION

FIG. 1 is a top, front and left side perspective view of a sterilization container showing my new design;

FIG. 2 is a top plan view thereof;

FIG. 3 is a bottom plan view thereof;

FIG. 4 is a front elevational view thereof, the rear elevational view being a mirror of that shown; and,

FIG. 5 is a right side elevational view thereof, the side opposite being a mirror of that shown.

1 Claim, 2 Drawing Sheets
